Fig. 2

Fig. 3

Fig. 5

Fig. 6

FIGURE 1 is a perspective view of a portable saddle rack embodying my new design;

FIGURE 2 is a front elevation of the same, with a portion of the supporting legs broken away;

FIGURE 3 is a rear elevation of the same;

FIGURE 4 is a left end elevation of the same;

FIGURE 5 is a right end elevation of the same; and,

FIGURE 6 is a bottom plan view showing the device in its portable condition and with portions of the leg members broken away for convenience of illustration.

I claim:

The ornamental design for a portable saddle rack, substantially as shown.
